UNITED STATES PATENT OFFICE

172,471

PLAYING CARD COUNTER

James F. Killoren, Falls Church, Va.

Application October 2, 1953, Serial No. 27,053

Term of patent 7 years

(Cl. D34—13)

To all whom it may concern:

Be it known that I, James F. Killoren, a citizen of the United States and a resident of Falls Church, State of Virginia, have invented a new, original, and ornamental Design for a Playing Card Counter, of which the following is a specification, reference being had to the accompanying drawing, forming a part hereof.

Fig. 1 is a perspective view of a playing card counter, showing my new design;

Fig. 2 is a side elevational view thereof; and
Fig. 3 is a front elevational view thereof.

I claim:

The ornamental design for a playing card counter, as shown.
